CHARLES C. FORNCROOK, OF HERMITAGE, NEW YORK.

Letters Patent No. 71,866, dated December 10, 1867.

IMPROVEMENT IN TUYERES.

The Schedule referred to in these Letters Patent and making part of the same.

TO ALL WHOM IT MAY CONCERN:

Be it known that I, CHARLES C. FORNCROOK, of Hermitage, in the county of Wyoming, and State of New York, have invented a certain new and useful Improvement in Tuyeres of Blacksmiths' Forges; and I do hereby declare that the following is a full and exact description thereof, reference being had to the accompanying drawings, making part of this specification, in which—

Figure 1 is a longitudinal vertical section of my improvement.

Figure 2, a plan of the valve-chamber with the cap *f* removed.

Like letters of reference indicate corresponding parts in both figures.

Blacksmiths' bellows, as commonly constructed, have their valves in the under side, which remain closed while the bellows are at rest, and, consequently, leave no access for the air to the fire, which soon expires, especially when anthracite coal is used.

It is the object of my invention to furnish a supply of air to the fire when the bellows are at rest, to keep it alive, and thereby prevent the inconvenience of relighting it, which is so often required, and which occasions such a loss of time, with the ordinary method of construction.

In the drawings, *A* represents the tuyere or nozzle of a pair of bellows; *B*, a valve-chamber on the upper side of the pipe, and communicating with the latter by a short tube, *e*, or in any other suitable manner. This chamber may be of any required construction, and is provided with a suitable valve, *d*, which will remain open when the bellows are at rest, or when there is no pressure of air from within, to permit the unobstructed entrance of the air, and that will close when the bellows are in operation to prevent the escape of the air. The valve *d* is provided with a stem, *e*, loosely fitting in a bridge, *g*, which is arranged in the chamber *B*, so as to be adjusted higher or lower by sliding therein, and thereby regulate the play of the valve, and consequently the amount of air admitted.

By the use of my improvement I have been enabled to keep alive for several hours a fire that would become extinct in a few minutes when the aperture of the valve was closed. It is desirable that the valve be arranged as near the end of the tuyere as practicable, as the draught to the fire is in proportion to the proximity of the valve.

What I claim as my invention, and desire to secure by Letters Patent, is—

The combination of the valve *d*, adjustable bridge *g*, chamber *B*, and tuyere *A*, arranged and operating substantially in the manner and for the purpose set forth.

In witness whereof, I have hereunto signed my name in the presence of two subscribing witnesses.

CHARLES C. FORNCROOK.
